LIQUID-SIREN SONIC AGITATOR

Arthur A. Fowle, Waltham, Mass., assignor to Ultrasonic Corporation, Cambridge, Mass., a corporation of Massachusetts

Application May 5, 1951; Serial No. 224,693

6 Claims. (Cl. 259—1)

The present invention relates to apparatus for treating bulk liquids with sound waves and comprises, in one aspect, a liquid siren.

It has long been recognized that sound waves of proper frequencies may be utilized to accomplish many valuable results when applied to liquids. For example, sound waves may be employed to kill bacteria, to accelerate the chemical processes involved in the ageing of alcohol beverages, to form emulsions, and otherwise improve the characteristics of many liquids. Attempts have been made to utilize piezo-electric crystals and magnetostriction rods as the source of sound waves in liquids, but the inefficiency of such operations on a large scale has precluded economic commercial use thereof.

The primary object of the invention is to provide simple and efficient apparatus for generating high intensity sound waves in bulk liquids and thereby to render commercially feasible the sonic treatment thereof.

An important feature of the invention resides in a rotor-stator combination wherein a liquid is introduced into the rotor and passed through the stator in bursts which generate pressure waves at sonic or ultrasonic frequencies, the arrangement of the rotor with respect to a surrounding housing being such that liquid discharged from the rotor drops at once into a drainage chamber beneath the rotor, whereby the rotor spins in air and is not subject to significant frictional drag of the liquid.

Still another important feature of the invention resides in a duplex conduit of which one-half serves as a passage for the supply of liquid to the rotor as well as for the passage of back-generated pressure waves, while the other part of the conduit serves for the passage of the liquid to be treated as well as a continuation of the passage for the pressure waves, the two portions of the conduit being separated by a plug having an acoustic impedance comparable to that of the liquid supplied to the rotor.

Another feature of the invention resides in a rotor having slots so formed that the passage of pressurized fluid therethrough serves to spin the rotor.

A very important feature of the invention resides in the combination of a hollow rotor and a surrounding stator so designed as to utilize the pressure waves generated within the body of the rotor itself, these waves traveling back through the rotor and into a treating chamber. This contrasts with conventional operation in which the pressure waves emanating from the stator are applied to do the desired work. While using the back-generated waves, it becomes possible to spin the rotor in air instead of liquid in order to reduce significant frictional drag. Furthermore the flow passages in the rotor may be designed so that turbulence within the rotor is avoided, thus increasing the effective amplitude of the back-generated waves. Moreover by supplying liquid to the rotor under pressure, cavitation affecting the back-generated waves is entirely eliminated, with the result that pressure waves of relatively large intensity may be generated and applied to do useful work.

These and other objects and features of the invention will be more readily understood and appreciated from the following detailed description of a preferred embodiment thereof selected for purposes of illustration and shown in the accompanying drawings in which:

Fig. 1 is a diagrammatic view of a complete liquid siren and sonic treating system.

Fig. 2 is a view in cross section through the elements 80 of the rotor-stator combination,

2

Fig. 3 is a plan view of the rotor-stator combination, with portions shown in section.

Fig. 4 is a view in cross section on an enlarged scale through a rotor slot, and

Fig. 5 is a view in cross section on an enlarged scale showing the relationship between the rotor slots and stator ports.

The general organization of a sonic treating system incorporating an improved liquid siren is shown in Fig. 1 wherein it will be evident that there is provided a large casing or housing 10 of generally cylindrical shape having a massive central boss 12 and also having in its interior an integral upstanding annular flange 14 provided at its upper end with a series of slots 16; this serves as a stator.

A shaft 18 extends through the boss 12 and is coupled at its lower end to a variable speed drive motor 20 resting upon a suitable base 22.

Registering with and secured to the housing 10 is an upper casing 24 having a massive central boss 26. A hollow rotor 28 is secured to the upper end of the shaft 18 within the chamber formed by the housings 10 and 24 and has a hollow chamber 30 and a series of peripheral slots or ports adapted to register with the slots 16 in the stator ring 14 and to open and close them as the rotor turns. The rotor is also provided on its upper surface with a centrally located aperture 34 surrounding which is a seal 36 by means of which the passage 34 is coupled in watertight relation to the flanged end of a vertical pipe 38 passing through the boss 26.

A conduit 40 connected to a pressure gauge 42 leads to the pipe 38 from a high pressure tank served by a variable drive pump driven by a motor 44 and arranged to supply liquid to the high pressure tank from a sump or low pressure tank connected to the bottom of the housing 10 by a drain conduit 46 and connected to the pump by a conduit 48. A by-pass conduit 50 connects the low pressure or sump tank to the high pressure tank and is provided with a pressure operated relief valve 52 which may be manually set to bleed the high pressure tank into the low pressure tank, at a predetermined pressure, and thereby automatically control the rate of flow of liquid from the high pressure tank into the pipe 38 and the rotor 28. There is provided in the pipe 38 above the conduit 40 a plug 54 of solid material having a compressibility similar to that of the liquid in the supply circuit and thereby exhibiting an acoustic impedance similar to that of the liquid, which may be oil of the sort commonly used in hydraulic systems. The plug 54 may therefore be composed of a rubber-like substance bonded to the pipe walls.

Above the plug 54 there is provided in the pipe 38 an inlet, and the upper end of the pipe 38 leads to a large surge tank provided with a pressure gauge 56 and also having an outlet or discharge pipe so that liquid to be treated may be circulated through the pipe 38 and into the surge tank in continuous fashion. The pressure gauge 56 permits observation as to the pressure in the treating system.

The rotor may be turned by the motor 20 as liquid is supplied to it. The flow of liquid through the rotor is intermittently interrupted as the rotor slots 32 pass in and out of registry with the stator slots 16. This periodic interruption of the flow of liquid generates compression and rarefaction waves both outwardly and inwardly with respect to the rotor slots. The inwardly directed pressure waves travel back through the pipe 38, passing easily through the plug 54 and thence into the liquid flowing in the upper part of the pipe and through the surge tank.

It is important to note that the rotor 28 spins in air, since liquid passing through the rotor slots and through the stator slots drops into the lower housing 10 from which it is immediately drained into the sump or low pressure supply tank. Consequently the movement of the rotor is not impeded by the frictional drag which would be present if the entire system were immersed in liquid. This feature is of great significance from the standpoint of the efficiency with which the system is operated.

As best shown in Fig. 3 the rotor may take the form

of a reaction turbine, in which case it supplies its own motive power from the pressure of the liquid and the motor may be eliminated. Where the motor is used to drive the rotor, the frequency of the sonic compression waves is a function of the speed of the motor and the number of slots in the rotor and stator, the rotor speed being the variable factor. Where the rotor is self-driven as a reaction turbine, the frequency will depend also upon the speed of the rotor, and that in turn will depend upon the pressure of the liquid supplied to it as well as the rate at which it is supplied, these factors being controlled by the setting of the relief valve 52 and the speed at which the pump is driven.

In Figs. 2-5 the rotor-stator combination is shown in greater detail. As before, there is provided a lower housing 60 having vertical reinforcing webs 62 terminating in an appropriately formed base 64. The housing 60 is provided with a centrally located tubular bearing housing 66 having an upper bearing assembly 68 and a lower bearing assembly 70, both being provided with suitable means for lubrication thereof. A shaft 67 is supported in the bearings and connected at its lower end to a motor shaft 69. Projecting upwardly from the bottom of the housing 60 there is an integral annulus 72 upon which there is mounted a stator ring 74 having a plurality of outwardly flaring ports or slots 76 and secured in position by a series of bolts 78. It should be noted that the stator is so constructed as to be readily removable and replaceable by one having slots of different configuration. In this way the shape of the generated sound wave may easily be varied and controlled. Change in the wave shape is accomplished by varying the flare angle of the stator slots. Within the stator and secured to the shaft 67 there is mounted a rotor consisting of a bottom disk 80 secured by two rows of screws 84 and 85 to an upper disk or plate 82. The bottom 80 of the rotor is machined to provide a circular central chamber from which radiate a plurality of milled slots 86 each of which terminates at the periphery of the rotor in tangentially inclined jets 88, the jets being inclined rearwardly with respect to the direction of rotation of the rotor.

A hollow casing 90 fits over the rotor and is secured to the lower housing 60 by a circumferential row of bolts 92. The housing 90 has a central tubular portion enclosing a sleeve 96 which bears at its lower end upon an annular sealing ring 94 resting upon the upper surface of the rotor disk 82 and flanged at its lower end to accommodate the lower end of a compression spring 98 which bears at its upper end against a plate 100. A pipe 102 pierces the plate 100 and is received within the interior of the sleeve 96. The spring 98 presses the flanged lower end of the sleeve 96, the seal 94 and the top of the rotor 82 in watertight relation. A packing gland or other suitable sealing arrangement may be employed in place of the system herein shown and described.

When liquid under pressure is supplied through the pipe 102 and into the interior of the rotor 80-82, it is forced outwardly of the rotor through the jets 88, and the reaction of this pressure through the jets 88 serves to spin the rotor with the shaft 67.

As the rotor turns the flow of liquid therethrough is interrupted as the stator slots are opened and closed. Preferably the speed of the rotor is governed to produce pressure pulses at a frequency equal to that of the natural frequency of the system including the pipe 102 and the tank which is coupled to it, since maximum amplitude is attained at this natural frequency. The sound waves traveling up the pipe 102 are reflected at the junction between the pipe and the surge tank, the result being that standing waves of considerable amplitude are established in the pipe.

Emphasis is laid upon the fact that the rotor spins in air, a fact which makes it possible to employ high rotor speeds, high frequencies, and high flow rates without wasting energy imparting angular momentum to fluid leaving the rotor. If it is desirable to produce cavitation in the liquid undergoing treatment, the supply system to the rotor may be operated under pressure while the pressure in the treating circuit is low; if cavitation is not desired, the treating circuit can be operated under sufficient pressure to prevent it and thereby to establish the standing wave field in the pipe. Preferably

the pipe is tuned to the siren either by adjustment or by precalculation.

Several important facts follow from the use of the back-generated pressure pulses instead of the more conventional utilization of the "down stream" generated waves. If the down stream generated waves were to be employed, the chamber surrounding the stator would have to be completely immersed in liquid. This liquid would exert a considerable frictional drag upon the rotor and thereby increase the work required to turn it. With the arrangement herein shown and described the rotor is spun in air, the most efficient manner of operation. Moreover, the flow passages in the rotor are streamlined to avoid turbulence within them, and the pressure pulses travel efficiently back through the rotor passages and into the treating system. By pressurizing the liquid supplied to the rotor cavitation within it is effectively suppressed, whereas the elimination of cavitation within the slots of the stator is difficult to avoid. Moreover it is practically impossible to avoid turbulence within the stator slots.

It is also important to note that the system herein shown and described makes it convenient to treat liquids in a confined system without passing them through the rotor-stator combination. Corrosive fluids or liquids of high viscosity could not for practical reasons be passed through the rotor-stator combination, but there is no impediment to passing them through a properly designed conduit and tank. As before stated the separation of the treating circuit from that of the rotor-stator combination also allows choice as to whether or not cavitation will be permitted within the treating circuit. Moreover the treating circuit may be separately tuned to resonance by increasing or decreasing the length of the conduit.

While there has been shown here a system designed for operation with a confined treating circuit, it is equally possible to employ the liquid siren as a means of generating pressure within an unconfined liquid. In such a case the inlet and surge tank are replaced by a suitable acoustic horn or other radiating device secured to the conduit.

A liquid siren of the type herein disclosed is useful to produce sound waves of high intensity and, generally, in the frequency range of from 100 to 1,000 cycles per second, although frequencies as high as 10,000 cycles may be obtained. The maximum sound output into water will exceed 10 kilowatts.

Having now described and illustrated a preferred embodiment of the invention, what I claim as new and desire to secure by Letters Patent is:

1. A liquid siren comprising a hollow rotor having peripheral openings, a stator surrounding said rotor and having ports adapted to be opened and closed by the rotation of the rotor, a first conduit connected to the rotor, a housing encasing said stator and providing a drainage chamber of large capacity beneath said rotor, means for supplying liquid to said conduit, a second conduit connected to said first conduit, a solid plug separating said conduits, said plug having an acoustic impedance comparable to that of said liquid, said first conduit and plug providing acoustical communication between said rotor and said second conduit, and means for passing liquid through said second conduit.

2. A liquid siren comprising a slotted rotor, a stator surrounding said rotor and having ports adapted to be opened and closed by the rotor, a first conduit connected to said rotor, means for supplying liquid to said first conduit and rotor, a second conduit connected to the first conduit, and a solid plug separating the first and second conduits, said plug having an acoustic impedance approximately equal to that of said liquid said first conduit and plug providing acoustical communication between said rotor and said second conduit.

3. A liquid siren comprising an elongated pipe, a hollow rotor connected to one end of said pipe, a stator surrounding said rotor, said rotor and stator having co-operating ports, a plug of solid material disposed in said pipe to separate it into two compartments, means for supplying liquid to the compartment nearest the rotor, and means for passing a liquid to be treated through the other compartment, said compartment nearest the rotor and said plug providing acoustical communication between said rotor and said other compartment, the

material of the plug having an acoustic impedance comparable to that of the liquid supplied to said rotor.

4. A liquid siren comprising an elongated pipe, a hollow rotor connected to one end of said pipe, a stator surrounding said rotor, said rotor and stator having cooperating ports, a plug of solid material disposed in said pipe to separate it into two compartments, a tank connected to the other end of said pipe, means for supplying liquid to the compartment nearest the rotor, and means for passing a liquid to be treated through the other compartment and tank, said compartment nearest the rotor, said plug and said other compartment providing acoustical communication between said rotor and said tank, the material of the plug having an acoustic impedance comparable to that of the liquid supplied to said rotor.

5. A liquid siren comprising a hollow rotor mounted for rotation upon a vertical shaft, a motor connected to said shaft, a housing surrounding said rotor and providing a chamber beneath it, a drain connected to said chamber, a stator disposed within said housing and surrounding said rotor, said rotor and stator having cooperating ports, a conduit mounted above and connected to said rotor, a plug of solid material disposed in said conduit to separate it into two compartments, means for supplying liquid to said rotor through one of said compartments, whereby liquid may be passed through the rotor and stator and chamber to said drain permitting

minimum frictional drag upon the rotor and means for passing a liquid to be treated through the other of said compartments in the said conduit, whereby said plug and the first-named compartment provide an acoustical communication between said rotor and said other compartment.

6. A liquid siren comprising a slotted rotor, a stator surrounding said rotor and having ports adapted to be opened and closed by the rotor, a first conduit connected to said rotor, means for supplying liquid to said first conduit and rotor, a second conduit connected to the first conduit, and a solid plug separating the first and second conduits, the first conduit and plug providing acoustical communication between said rotor and said second conduit, said plug having an acoustic impedance approximately equal to that of said liquid.
